UNITED STATES PATENT OFFICE.

JEFFREY T. FERRES, OF ANDERSON, INDIANA, ASSIGNOR TO J. W. SEFTEN
MANUFACTURING COMPANY, OF ANDERSON, INDIANA, AND CHICAGO,
ILLINOIS, A CORPORATION OF INDIANA.

CORRUGATED PAPER-BOARD.

No. 825,307.

Specification of Letters Patent.

Patented July 10, 1906.

Application filed December 26, 1905. Serial No. 293,340.

To all whom it may concern:

Be it known that I, JEFFREY T. FERRES, a citizen of the United States, residing at Anderson, Madison county, Indiana, have invented certain new and useful Improvements in Corrugated Paper-Board, of which the following is a specification.

My invention relates to corrugated paper-board, more particularly the double-faced type; and the object thereof is to provide means for reinforcing or stiffening one or more of the edges of such board.

My invention has special, but not exclusive, application to what are commonly known as "calendar-mailers," which require to be particularly stiff in order to prevent the calendars from being bent or broken in the mails.

Various other features of advantage and utility of my invention will be understood from the description hereinafter given.

In the drawings, Figure 1 is a perspective of a calendar-mailer embodying my invention; Fig. 2, a side or edge elevation thereof, and Fig. 3 a perspective of one of the strengthening-strips shown ready for insertion in the paper-board.

For purposes of convenient illustration and description I have shown my invention as applied to a calendar-mailer; but it will be understood that my invention is not to be limited to this particular use of corrugated paper-board, but that I contemplate using my invention wherever applicable. As shown, the calendar-mailer comprises a corrugated paper-board A of suitable size and dimensions and provided with the paper flap A', one of whose edges is secured in suitable manner to one side of the paper-board.

The paper-board A, which is to be strengthened or stiffened at one or more of its edges for the purposes hereinbefore stated, is what is commonly known as "double-faced" corrugated paper or board, comprising the two facing-strips a and a' and the intermediate corrugated paper a². The strengthening-strips, which, as shown in Fig. 1, are two in number, consist of wood strips or veneer B, which by preference are driven or crowded in a suitable manner through the corrugations and preferably across such corrugations, as seen in Figs. 1 and 2. Moreover, in practice, more particularly in calendar-mailers, it is

preferred to insert the strips a short distance from the edge of the corrugated sheet—say about one-half an inch therefrom—such strips not only preventing bending of the board or sheet, but also preventing the corners of the sheet from being crushed down, which has been a serious fault with the old style of calendar-mailer.

Although I prefer to insert or force the wood strips or veneer through the body of the corrugations, as above explained, yet it is possible to apply the wood strips by placing them in position on top of the corrugations and then applying the second lining-sheet over them. It will be understood that such modification is within the scope of my invention.

In practice the wood strips or pieces B are inserted by machinery which applies glue, gum, or other similar substances to both sides of the stick. In order to enable the strips to be forced or driven readily through the corrugations, such strips are first sharpened at one end and are forced through the sheet so as to protrude therefrom, say, about three-fourths of an inch on the opposite side. The strips are thereupon cut off smooth with the edge of the sheet, or, if desired, instead of sharpening the strips the same before being driven may be inserted in a metal point having a socket at its rear end, and thereupon forced through the sheet or board, after which such metal point can be removed and placed on another strip to be forced through the sheet or board.

Inasmuch as corrugated paper-board is more liable to bend or break longitudinally of the corrugations, it is preferable to insert the reinforcing or stiffening strips transversely of such corrugations, as is shown in Figs. 1 and 2; but it will be understood that some measure of my invention may be obtained by inserting such strips longitudinally of the corrugations.

Corrugated paper-board provided with strips as hereinbefore described has nearly the same strength and resistance as a solid wooden board, with all liability of bending in the body or crushing at the corners prevented.

I claim—

1. In a corrugated paper-board, a strengthening-strip embedded in the corrugations.

2. In a corrugated paper-board, a strengthening-strip forced through the corrugations transversely thereof.
3. In a corrugated paper-board, a strengthening-strip forced through the corrugations along an edge of such board.
4. In a corrugated paper-board, strengthening-strips forced through the corrugations along two opposite edges of such board.
5. In a double-faced paper-board, strengthening-strips forced through the corrugations and between the facings of the board.
6. In a double-faced paper-board, strengthening-strips embedded in the corrugations transversely thereof and between the facings ¹⁵ of the board.
7. In a corrugated paper-board, strengthening-strips forced through and glued to the corrugations of such board.

JEFFREY T. FERRES.
